UNITED STATES PATENT OFFICE

JOHN P. WEIS, OF NYACK, NEW YORK, ASSIGNOR TO METROPOLITAN SEWING MACHINE CORPORATION, OF NYACK, NEW YORK, A CORPORATION OF DELAWARE

POWDER-PUFF-SEWING MACHINE

Application filed October 27, 1926. Serial No. 144,425.

This invention relates to sewing machines, the object thereof being to provide an improved machine which, while particularly adapted for stitching powder puffs, may also be used for stitching pockets, bags, 5 watch covers, pouches and other circular, oval or similarly shaped articles usually made by stitching together a plurality of superimposed layers of fabric in which the 10 stitches extend completely or part way around the outer edges to leave an unstitched portion or opening sufficient to permit the article to be turned inside out with the raw edges of the seam on the inside. 15 While the machine is also useful for applying bindings, lace, embroidery or other edging to such shaped articles and may be provided with any of the well known guides, formers, folders, rufflers, gatherers or trimmers, which may be used with a circular 20 feeding of the work, the primary object of the present invention is the provision of an improved machine, simple in construction and operation and practically automatic, for 25 stitching powder puffs made from plush or velour fabric in which the plush or velour faces are juxtaposed for the stitching operation, and in which the stitch line preferably extends around the article a predetermined 30 distance, thereby leaving an opening of about fifty degrees to permit the article to be turned inside out and thus bring the plush or velour faces on the outside, subsequent to which the unstitched portion is closed by 35 hand stitching.

Another object of the present invention is the provision of an improved machine for stitching circular or similarly shaped articles and also irregular forms in a quick and efficient manner and in which all that the operator has to do is to place the work between circular clamp plates and depress a treadle, whereby the manual labor of operating the machine is reduced to a minimum and the 40 output of the machine materially increased, while a more uniform product is obtained.

A further object of the invention is the provision of an improved machine which will stitch circular or other similarly shaped articles in such manner that the stitching will

be a true circle so as to leave a uniform margin from the stitch line so that when the article is turned inside out there will be a uniform appearance all around the same and no objectionable bulking of the goods, 55 and in which machine the same number of stitches is used regardless of the size of the article, and which machine is thrown into operation by the simple pressure upon a treadle and thereafter automatically operates to start the stitching at a predetermined point, and stopped at a predetermined point with the needle out of the work and the work 60 released from its clamp plates with the thread ends of the stitch lines of sufficient length 65 to prevent raveling back when the article is turned inside out.

A further object of the invention is the provision of an improved machine of the class described in which the superimposed 70 pieces of work are so controlled as to prevent one layer thereof from shifting upon the other, thus preventing puckering, gathering or undesirable fullness of the stitched article.

A further object of the present invention is the provision of automatically operated work clamp plates, readily changeable for plates of different diameters, together with 75 means for circularly feeding said plates and which plates are mounted on a swinging bracket whereby different sizes of work may be readily and uniformly stitched, and which is combined with a cylinder sewing machine in such manner that all that is necessary for 80 the operator to do is to press the foot treadle or other means which may be used for starting the machine, whereupon the machine starts and completes the stitching of the circular form and stops at a predetermined 85 position with the needle out of the work and the work automatically unclamped so that the operator merely removes the stitched article and places the next article in position for stitching at which time the threads of 90 the previously stitched article are automatically clipped by a cutter adjacent to the stitching position of the needle.

In the present improved machine, which 95 may be arranged for making any desired 100

form of stitch including a single thread chain or a two thread chain stitch, and have a suitable automatic tension release to release the thread, the organization is such that there is 5 always a given number of stitches used in the stitching of each article regardless of its size or diameter, as the length of the stitches increases with the diameter of the article so that, for instance, if 300 stitches are placed 10 in a three inch powder puff, the same number of stitches will be placed in a three and a half or four inch powder puff, and this has considerable to do with the output of the machine, for otherwise it would take longer to 15 stitch a large powder puff than a small one. Furthermore the application of this improvement to a cylinder machine very materially increases the convenience in handling the work, the threading, cleaning and oiling, and so far as I am aware this is the first cylinder 20 sewing machine adapted for the circular stitching of the articles hereinbefore mentioned.

In the drawings accompanying and forming 25 a part of this specification, Fig. 1 is a perspective view of this improved machine, with the transmitter, foot treadle control and certain details omitted.

Fig. 2 is also a perspective view thereof 30 at the opposite side of Fig. 1.

Fig. 3 is a side view partly in section of the machine with the transmitter and foot treadle control connected therewith for starting and stopping the machine.

Fig. 3a is a detailed view showing the anti-friction bearing at the top of the work clamp 35 with a part of the presser bar spring resting thereon.

Fig. 4 is a top plan view of a portion of this improved sewing machine illustrating the 40 manner in which the thread extending from the stitch mechanism to the previously stitched article, moved to the left or cutting off position, is severed by a thread cutter 45 which is located adjacent to the needle for convenience in separating one article from another after the stitching operation.

Fig. 5 is a detail sectional view of the ratchet feed mechanism.

Fig. 5a is a detail view of a part of the ratchet feed mechanism.

Fig. 6 is a perspective view of the ratchet feed mechanism.

Fig. 7 illustrates the throat plate, the 55 thread cutter, a portion of the feeding mechanism, and the position of the needle relative thereto.

Fig. 8 is a diagrammatic view showing the circular ratchet feed mechanism, the work 60 guide, throat plate and thread cutter and also a portion of the feed operating mechanism. The view also shows the gearing operated by the ratchet feed for tripping the stop motion to control the size of the unstitched portion 65 of a powder puff or other article.

Fig. 9 is a detail view representing a powder puff as stitched by the machine.

Fig. 10 illustrates the powder puff after it is turned inside out.

Fig. 11 illustrates a pouich having two 70 parallel edges and a round bottom.

Fig. 12 represents a circular article such as a pouich or powder puff with a binding applied to the edges.

Fig. 13 shows the feed operating parts.

Fig. 14 is a detail plan view showing how 75 the circular feeding mechanism can be arranged to feed and stitch irregular forms.

Similar characters of reference indicate 80 corresponding parts in the several figures of the drawings.

Before explaining in detail the present improvement and mode of operation thereof, I 85 desire to have it understood that the invention is not limited to the details of construction and arrangement of parts which are illustrated in the accompanying drawings, since the invention is capable of other embodiments, and that the phraseology which I 90 employ is for the purpose of description and not of limitation.

The present improvement is illustrated in 95 connection with the well known Metropolitan cylinder sewing machines heretofore patented to me for instance in Patents No. 1,348,527, dated August 3, 1920, No. 1,352,333 dated September 7, 1920, and Patent No. 1,581,764, dated April 20, 1926, and which cylinder machine offers important advantages in that 100 the entire mechanism for operating the needle, looper and feed is carried in the trunk of the machine frame remote from these elements, thus providing ample space for convenience in handling the work as well as offering other advantages that will appear in 105 this specification.

This cylinder machine is equipped with 110 automatic starting and stopping mechanism, automatic lubricating mechanism and automatic thread control, and the novel features of the present invention reside principally in the rotary work clamp and its feeding mechanism, thread cutter and automatic operation of the machine and the associated parts necessary to apply the same to a cylinder sewing machine.

In the drawings accompanying and forming 115 a part of this specification, the sewing machine frame includes a trunk 1 having a pair of forwardly projecting arms, one an overhanging arm and the other shown as a cylinder, and this trunk carries a handwheel 2 for turning the machine operating parts by hand. A belt guard 3 encloses the belt 4 which is operated by a transmitter, indicated generally by 5, see Fig. 3, comprising a tight and a loose pulley or clutch. A rod 6 is connected to a foot treadle 7 pivoted at 8 to a support 9 secured to the floor. The forward end 10 of the foot treadle is manipulated 120

5 by the foot of the operator. Underneath this treadle is a spring 11 in position to force the treadle upward. Any suitable spring may be used for this purpose, as for instance a pull spring attached to the underside of the table and connected to the rod 6 in any suitable manner.

10 The rod 6 is pivoted at 12 to the control lever 13 of the transmitter. A rod 14 is also connected to the control lever by adjustable collars 15 and forms the connecting means between the sewing machine stop motion mechanism and the transmitter. The transmitter is also provided with suitable speed regulating means 16 for regulating the friction drive of the pulley clutch. An idler pulley 17 may be used when necessary to keep the front run of the belt in proper position.

15 The machine and transmitter are mounted upon a suitable work table 18. Rod 14 operates freely through this table and is provided with a notch 19 for the purpose hereinafter described, and by means of a coupling 20 the upper end of this rod is connected with the lower end of a rod 21. This rod 21 25 has a sliding connection with the stop motion mechanism of the sewing machine which is fully described in the patents to which reference has hereinbefore been made, and which includes a stop motion lever pivoted to the trunk at 22.

20 Attached to the front wall of the machine trunk are bearings 23, see Figs. 2 and 3. A vertical shaft 24 is mounted in these bearings and supports a swinging frame or bracket A which is likewise provided with bearings 25 and 26. This frame swings freely on shaft 24. The forward end of this frame A terminates in bearings 27 and 28 in which 30 a presser bar 29 is supported for up and down movement and also for rotation. The upper end of this bar is provided with a center 30, see Figs. 3 and 3a, in which is seated a ball 31. The forward end of the presser bar spring 32 presses the bar 29 downward. A ball weight 32a mounted directly on top of the bar 29 may be used in place of this spring. The advantage of the weight is that the pressure is uniform, whereas with the spring there is a slight increase in tension as the bar is lifted. In order that the bar may have a vertical movement of about 1½ inches and yet have a minimum variation in tension, the spring when used is provided with a loop 33 which gives a greater yielding action, so that the tension of the spring is unchanged when the bar is either up or down. To regulate the pressure of the spring, an adjusting screw 34 tapped into a lug carried by the swinging frame, is provided. The rear end of the spring 32 rests on the top of the vertical shaft 24. To lift the presser bar 29, the upper end of stop motion operating rod 21 is employed to act

35 against the weighted end 37' of a lever pivoted at 38 to a bracket or lug carried by the machine trunk. The forward end 39 of this lever 37 overhangs the end 40 of a lever 42 pivoted at 41 to the swinging frame, and the forward end of the lever 42 is forked to straddle the presser bar 29 and act against a collar 43 thereon to lift the bar 29 against the action of the spring 32 or the weight of the ball 32a, whichever is used.

40 The end 39 of the lever 37 is of considerable width so that as the swinging frame A is swung on its shaft 24 these levers will remain in operative relation. The opposite end of the lever 37 which cooperates with the rod 36 is weighted, as at 37', to overbalance this lever and normally hold that end of the lever down. The lower end of the presser bar 29 is tapered, see Fig. 5, to make a drive fit in the circular disk or top clamp plate 44, 45 which is provided with a hub 45. This disk 44 may be provided with openings 45a to give a better gripping action on the work and thus prevent the work from slipping between the work clamp plates. This also permits a 50 lighter pressure to be used.

55 The hub 45 may be provided with a set screw 45' to clamp it in position. This clamp plate is similar to the bottom work clamp plate 46 which is also provided with a hub 47 and a set screw for securing it in position. The bottom plate is also carried on the tapered end 48 of a shaft 49. This shaft is rotatable in bearings 50 and 51, which are part of the swinging frame A. These bearings are supported and connected by a web formed bracket 52 of the swinging frame A forming a rectangular opening in which is located the feed mechanism 53 for rotating the clamp plates or work turn table.

60 Extending forwardly of this webbed bracket 52 is a work supporting bracket 54 to which is secured a work table 55, which is changed when the work plates are changed for larger or smaller diameter plates. The table has a semicircular cutout portion conforming to the work plate. These work tables are made in different sizes to suit the character of article to be stitched by the machine, as for instance a 2-inch diameter work clamp plate would require one size of work table while a 5-inch work clamp plate would require a larger size of work table. Different sizes and diameters of plates are provided to suit the size, shape or kind of work required. Since these tables have to be changed frequently, fastening means 56 therefor is provided so that they may be quickly attached or removed; and since the rotary work clamps or plates 44 and 46 have also to be changed for different sizes of articles, it is desirable to have them arranged for quick attachment and removal. Any means such as the taper and set screws described and which can be quickly manipulated to facilitate

tate their adjustment to a fixed position relative to the other parts, may be used, as the changing of these parts is usually done by the machine operator.

Fixed to the lower end of the shaft 49, see Figs. 3, 5 and 8, is a gear 57 in mesh with and operating a gear 58 pivotally secured to the under side of the swinging frame A by means of an adjustable stud 59. This gear 58 carries a pin 60 projecting downward which 10 acts with a roller 61 carried by a stud 62 secured to a lever 63 pivoted at 64 to the swinging frame A.

To the upper end of this lever 63 as at 65 is secured a trip rod 66 which is under the 15 control of a spring 67, one end being connected thereto and the other end connected as at 68 to the machine frame. The rear end of the rod 66 is bent downward as at 69, and has pivotally connected thereto a slide bar 70 which is slidably supported in the bottom 20 of the machine trunk. The rear toothed end 71 of this slide is in position to engage the notch 19 of the rod 14. The slide is so located as to have the center of its bent end 69 25 in line with the vertical axis of the shaft 24 so that the swinging frame A may swing in and out toward and from the cylinder without binding or cramping the trip rod 66. The normal tension of the spring 67 keeps the ends 30 71 of the slide 70 against the rod 14 so as to shift into the notch 19 instantly as the rod 14 is depressed at the time the machine is started, thus maintaining the machine in operation 35 until the pin 60 carried by the gear 58 makes a complete revolution, at which time the trip mechanism will be operated, and the end 71 of this trip slide will be withdrawn from the notch 19 and the machine stopped by the 40 stop motion mechanism.

If gear 58 is smaller in diameter than the gear 57, it will make a complete revolution proportionately faster and thereby trip the stop motion rod 14 by withdrawing the toothed end 71 thereof from the notch 19. 45 The treadle spring 11 cooperating with the stop lever springs thereupon acts to force the rods 6, 14 and 21 upward and bring the machine to a stop. If on the other hand it is 50 desired to have the machine stitch completely around a circle, both gears 57 and 58 would have the same diameter; or if it is desired to have the stitches overlap after stitching the complete circle for about $\frac{1}{4}$ or $\frac{1}{2}$ inch, then the gear 57 would be a trifle smaller in 55 diameter than would be the gear 58.

The ratio of these gears governs the distance of the stitch line around the article, either to leave an unstitched opening or to 60 overlap the stitching to secure the beginning and ending of the stitch line, as the case may require.

The circular feed mechanism shown here- 65 in has a ratchet mechanism 53, see Figs. 1, 5, 5a and 6, is secured to the shaft 49 and posi-

tively drives this shaft with an intermittent motion. The shaft 49 turns when the needle is out of the goods. Any suitable intermittent feed mechanism may be used for giving rotary motion to the shaft 49 and work clamps. In 70 fact, for the majority of materials a continuous drive may be employed, as the needle is in the work but an instant and the flexibility of the material would permit the successful use of the continuous feed motion. Preferably, however, the intermittent feed 75 comprises a feed wheel 72 recessed at 73 to receive a ratchet lever 74 having a hub 75 telescoping the hub 76 of the feed wheel. The ratchet lever hub has a flange 77, see 80 Fig. 5a, and also a flange 78 terminating in a lever end 79 connected to an arm or lever 80 by a bolt 81. This ratchet feed lever 74 carries four feed pawls 82 freely pivoted between the flanges 77 and 78 on pins 83. Connected to each pawl is a tension spring 84, the other end of which is connected also to a pin carried by the feed lever. These four 85 pawls grip the feed wheel so as to positively shift it step by step to properly space the 90 stitches. To prevent back drag or slippage, a back lash pawl or dog 85, under the control 95 of a pull spring 85a, see Fig. 8, is pivoted at 86 to the swinging frame A. This pivot 86 is in the form of an eccentric stud which thus provides a means of adjustment for the back 100 lash pawl. The feed wheel 72 is provided with a metal cover 88 to prevent lint and dirt from interfering with the action of the feed 105 pawls.

The intermittent feed is operated by the feed bar located in the cylinder of the machine and for this purpose a lever 89 having forked ends 90 engages the lever 80 of the ratchet feed. The upper end of the lever 89 105 is bent at right angles and has its bent end 92 secured to the feed bar 93 supported in the cylindrical arm or cylinder 94 of the machine by a link 95, see Fig. 13. The rear end of this bar is pivotally connected at 96 to a 110 feed operating lever 97 which slidably engages fulcrum 98. The upper end of the feed lever 97 is connected with the crank arm of a crank shaft 99. The vertical post 100, see 115 Fig. 13, contains an adjusting mechanism for raising and lowering the fulcrum 98 to lengthen or shorten the throw of the feed bar which in turn lengthens or shortens the movement of the circular feed, thereby changing 120 the length of the stitch.

The stitching mechanism of the sewing machine comprises a needle mechanism indicated generally at 101 carried by the overhanging arm of the sewing machine, see Fig. 2, a presser foot indicated at 102, and a looper 125 mechanism 103 carried by the cylinder. A throat plate 104, see Fig. 7, is attached to the cylinder 94 and is provided with the usual needle hole 105 in its forward end. This throat plate has a curved cutout por- 130

tion 106 to provide working space for the rotary work clamps. Adjustably attached to the throat plate at the left of the needle hole, see Figs. 7 and 8, is a cutting mechanism comprising a stationary knife or blade 107, and co-operating therewith is a movable knife or blade 108 pivoted in the throat plate at 109. The lower depending portion of this movable knife or blade terminates in a forked end 110 engaging a pin 111 carried by the forward end of the feed bar 93. As the feed bar moves endwise this pin gives rocking movement to the knife or blade 108, which thus acts as a shear against the stationary knife so as readily to cut the chain of stitches or frayed ragged edges of the articles as they are being stitched.

To hold the swinging frame A in working position relative to the needle, either a slotted link 112, see Fig. 4, or a spring 116, see Fig. 14, attached to a collar 113 is used. This collar is clamped on the cylinder 94. The link is adjustably secured in position by a clamp screw 114, see Fig. 1. The other end of the link is connected, as at 115, to the bottom of the swinging frame A.

For stitching irregular forms, I substitute for this rigid link connection the spring 116 normally to pull the swinging frame toward the needle. Adjacent to the operating position of the needle is mounted a roller 117, see Fig. 14, which may act against a form plate or pattern 118 carried by, or forming part of, the work clamp 119, so that as such work clamp rotates, the cam plate will act against the roller to swing the bracket A on its vertical shaft 24 so as to stitch irregular form outlines in accordance with the shape of the pattern or form 118.

The article shown in Fig. 11 may be stitched by such a pattern and represents a watch case cover or similar pouch which is stitched all around the marginal edges from starting point B to finishing point C. Fig. 9 represents a circular powder puff, the stitch beginning at B and ending at C. The ribbon or handle is indicated at D. One end is stitched in at E while the other end is free, as at F. Fig. 12 represents a powder puff or similar article with a binding G. When a pattern of irregular form is used and the stitching interrupted to leave an opening as in Fig. 11, it is merely necessary to shift the pattern by hand in the direction of the feed of the work from the position shown in Fig. 14 where the stitching is ended as at 117, to a position on the opposite corner, where the stitching starts, as at 117a.

In the stitching of a circular piece such as a powder puff, Fig. 9, the work is shifted independently of the clamp plate. There is no need of shifting the circular clamp, but with an irregular form, having one portion of the form conforming to the opening of the work, it is merely necessary to turn the pattern by

hand to a position for starting each piece. This is a very simple matter, since the feed is a friction feed and is readily shifted in the direction of the feed of the work. This of course could be easily done by suitable mechanical automatic means for making this shift each time the work clamps are separated, but the present arrangement offers some advantage in that when the work is placed, the open straight end of the article is in such a position as to make it most convenient to register the article with the pattern because that portion is nearest the operator at such time.

The number of stitches employed with respect to the length of the stitch are arranged to stitch around from B to C only.

For conveniently and quickly placing circular articles, such as powder puffs, between the rotary work clamps, a curved guide 119a, see Fig. 8, is attached at 119' to the work plate 55. This guide is adjustably secured at 120 to a plate 121 so that its curved end 122 will position the powder puffs with respect to the center of the circular work clamps 44 and 46. This guide is adjustable to conform to the different sizes of table and clamp plates which are used. This guide is a very narrow piece of metal, about $1\frac{1}{4}$ " in height and the forward end 119a, Fig. 8, may be lower than the rest of the guide, and, as the work is of very flexible material, the irregular projections of the work come right up over the top of this guide. In fact, after the operators become experienced, these guides are usually removed entirely from the machine. The setting of the work is then gauged entirely by the work clamp. As a matter of fact, the guide positioned as shown in Fig. 8 could be used when stitching an article like Fig. 11, since the guide would serve to locate the circular portion of the article, while the work is being placed between the clamp plates.

Attached to the cylinder of the machine is a suitable guard 125, see dotted lines Fig. 1, which serves not only to guard a part of the feed mechanism, but also acts as a shelf or rest for the stitched powder puff or other article after it is completed and upon which it rests until the thread X, see Fig. 4, is severed by the knife, whereupon it is removed or falls into a suitable receptacle.

The operation of the machine is as follows:

The operator assembles the sections of the powder puff or other article and places them in position on the lower work clamp or plate 46 at which time the top clamp plate 44 is in its uppermost position (about $1\frac{1}{2}$ inch space is provided between the two plates for convenience in placing the work). The treadle 10 is depressed by the foot of the operator, whereupon the transmitter clutch is thrown into operation, being driven from a suitable source of power, as a motor, and operates the belt 4. Simultaneously with this action the

rods 14 and 21 are shifted downward, thus releasing the upper clamp plate and permitting its spring 33 or weight 32a to shift this plate downward and clamp the work, whereupon the clutch of the sewing machine shaft engages and the machine starts the feeding and sewing. The trip pin 60 carried by the gear 58 rotates away from the roller 61, thus causing spring 67 to shift the slide 70 so that its toothed end 71 engages the notch or tooth 19 of the rod 14 and holds it down whereupon the operator may remove his foot from the treadle 10 since the machine continues to operate until the pin 60 makes a complete rotation and operates the trip mechanism to release the toothed end 71 of the slide bar from the notch 19. In other words the machine stitches the circle until the pin 60 rotates into engagement with the roller 61 which thus shifts the lever 63 and the trip slide 70 to withdraw its toothed end 71 from the notch 19 of the rod 14. The action of the spring 11 and the springs carried by the stop motion mechanism return the parts to their normal upward position, the transmitter clutch is disengaged, the sewing machine clutch is also disengaged and the machine stops instantly with the needle at its highest position.

The upward movement of the rod 21 shifts the levers 37 and 42 on their pivots 38 and 41, so as to lift the top work clamp 44 against the action of the spring 33 or against the pressure of the weighted ball 32a, when this is used in place of the spring 33. The stitched article is then removed to the left and another article placed for stitching. Instantly as the machine starts the thread or chain of stitches indicated by X in Fig. 4 is brought into engagement with the knife 108 and severed thereby.

From the foregoing it will be understood that the operation of stitching circular or irregular forms merely requires the placing of the work in position between the clamp plates and pressing the treadle to start the machine. The number of stitches as well as the length of openings is predetermined regardless of shape, size or diameter of the articles being stitched. By reason of these improvements more uniform work and a considerable increase in production results, for all that the operator has to do is to place the work in position, press the foot treadle, whereupon the machine starts and completes the stitching and stops at a predetermined position. The work is unclamped automatically, whereupon the operator merely removes the stitched article and places the next articles in position for stitching. The chain of stitches or threads at the end of the stitching operation is automatically clipped by a cutter located adjacent to the needle as the stitching of a succeeding article is com-

menced, whereupon the stitched article is removed or falls into a suitable receptacle.

From the foregoing it will be observed that a single treadle controls the entire operation of the machine and that by pressing this treadle the work is first clamped and the machine started and the powder puff or other article sewed whereupon at a predetermined time the trip mechanism releases the rod 14 and the machine is automatically stopped whereupon the work is automatically unclamped.

In this improved machine it will be observed that the work clamps will be rotated as long as the machine is kept in motion since the release of the work clamps takes place only after the machine is stopped. In other words, continued pressure upon the treadle will maintain the machine in continuous operation if desired, whereas should a separate treadle be used to control the work clamps, the inadvertent manipulation of this treadle would result in the immediate unclamping of the work while the machine was in motion so that the work would cease to rotate and the stitches pile up, whereas in the present improvement the machine and the operation thereof is under the control of a single element or treadle.

In practice the operating belt 4 could run directly to a suitable source of power and the transmitter entirely done away with since the crank shaft of the sewing machine contains a clutch as set forth in the patents hereinbefore referred to, in which case the rod 6 would be coupled directly to the rod 14. In such instance, the belt 4 would be in continuous operation but the machine would start and stop precisely as though the transmitter were used.

It is to be understood that by describing in detail herein any particular form, structure or arrangement, it is not intended to limit the invention beyond the terms of the several claims or the requirements of the prior art.

Having thus explained the nature of my said invention and described a way of constructing and using the same, although without attempting to set forth all of the forms in which it may be made, or all of the modes of its use, I claim:

1. In a sewing machine having stitching mechanism and feed operating means, the combination of a rotary turn-table for feeding the work, and mechanism operated from the feed operating means and directly connected with the turn-table for positively and directly rotating said turn-table, whenever said feed operating means is operated.

2. In a sewing machine having stitching mechanism and feed operating means, the combination of a rotary turn-table for feeding the work, ratchet mechanism operated from the feed operating means and directly

connected with the turn-table for positively and directly rotating said turn-table whenever said feed operating means is operated and cooperating means for stopping the stitching mechanism with the needle at its highest point.

3. In a sewing machine having stitching mechanism and feed operating means, the combination of a rotary turn-table for feeding the work, ratchet mechanism operated from the feed operating means and directly connected with the turn-table for positively and directly rotating said turn-table whenever said feed operating means is operated, and cooperating means for stopping the stitching mechanism with the needle at its highest point, said cooperating means comprising tripping means operated by the ratchet mechanism and comprising a pair of gears, a stud carried by one of said gears and shiftable means operated by said stud.

4. In a sewing machine having a trunk and an overhanging arm carried thereby for the needle of the stitching mechanism, the combination of a swinging bracket pivotally connected adjacent to the rear end of said arm and shiftable toward and from the stitching mechanism, a work turn-table carried by said swinging bracket, and means for rotating said turn-table and thereby the work.

5. In a sewing machine having a trunk and an overhanging arm carried thereby for the needle of the stitching mechanism, the combination of a swinging bracket pivotally connected adjacent to the rear end of said arm and shiftable toward and from the stitching mechanism, a work turn-table carried by said swinging bracket, means permanently connected with the turn-table for positively and directly rotating said turn-table and thereby the work, and means for automatically stopping the machine with the needle in the highest point.

6. In a sewing machine having a trunk and an overhanging arm carried thereby for the needle of the stitching mechanism, the combination of a swinging bracket pivotally connected adjacent to the rear end of said arm and shiftable toward and from the stitching mechanism, a work turn-table carried by said swinging bracket, and comprising a pair of work clamp plates one shiftable toward and from the other, means for rotating said turn-table and thereby the work, and means for automatically clamping and unclamping the work.

7. In a sewing machine having a trunk and an overhanging arm carried thereby for the needle of the stitching mechanism, the combination of a swinging bracket pivotally connected adjacent to the rear end of said arm and shiftable toward and from the stitching mechanism, a pair of rotary work clamp plates carried by said bracket, means for intermittently rotating said plates, and

thereby the work, and means for automatically stopping the stitching mechanism and the rotation of the plates at a predetermined time.

8. In a sewing machine having a trunk and an overhanging arm carried thereby for the needle of the stitching mechanism, the combination of a swinging bracket pivotally connected to said trunk at the rear end of said arm and shiftable toward and from the stitching mechanism, a pair of changeable rotary work clamp plates carried by said bracket, means for intermittently rotating said plates, and thereby the work, and means for automatically stopping the stitching mechanism and the rotation of the plates at a predetermined time.

9. In a sewing machine having an overhanging arm and stitching mechanism, a bracket shiftably connected adjacent to the rear end of and extending approximately parallel to said arm and shiftable toward and from the stitching mechanism, rotatable work supporting means carried by the bracket, and means for intermittently feeding said work supporting means and thereby the work, and means for automatically starting and stopping said feeding means at predetermined points.

10. In a sewing machine having a trunk and an overhanging arm carried thereby for the needle of the stitching mechanism, a swinging bracket pivotally connected to said trunk at the rear end of said arm and shiftable toward and from the stitching mechanism, rotatable work supporting means carried by the swinging bracket, means for intermittently feeding said work supporting means and thereby the work, and means for automatically starting and stopping said feeding means at predetermined points.

11. In a sewing machine having stitching mechanism and feed operating means, a bracket shiftable toward and from the stitching mechanism, rotatable work supporting means carried by the bracket, means connected with the feed operating means and directly and positively connected with said work supporting means for positively intermittently feeding said work supporting means whenever said feed operating means is operated, and means for automatically starting and stopping said feeding means at predetermined times.

12. In a sewing machine having stitching mechanism and feed operating means, a bracket shiftable toward and from the stitching mechanism, rotatable work supporting means carried by the bracket, means connected with the feed operating means and directly and positively connected with said work supporting means for positively intermittently feeding said work supporting means whenever said feed operating means is operated, means for automatically start-

ing and stopping said feeding means at predetermined times, and means for automatically clamping and unclamping the work carried by the work supporting means.

13. In a sewing machine having stitching mechanism and feed operating means, a bracket shiftable toward and from the stitching mechanism, rotatable work supporting means carried by the bracket, means connected with the feed operating means and directly and positively connected with said work supporting means for positively intermittently feeding said work supporting means whenever said feed operating means is operated, means for automatically starting and stopping said feeding means at predetermined times and for starting and stopping the stitching mechanism, and means for automatically clamping and unclamping the work carried by the work supporting means.

14. In a sewing machine having a trunk and an overhanging arm carried thereby for the needle of the stitching mechanism, a swinging bracket pivotally connected adjacent to the rear end of said arm and shiftable toward and from the stitching mechanism, rotatable work supporting means carried by the bracket, and comprising a pair of changeable clamp plates, means for intermittently feeding said work supporting means and thereby the work, and means for automatically starting and stopping said feeding means at predetermined points.

15. In a sewing machine having a trunk and an overhanging arm carried thereby for the needle of the stitching mechanism, the combination of a bracket pivotally supported at the rear end of the arm for shiftable movement toward and from the stitching mechanism, rotatable work supporting means carried by said bracket, means for intermittently feeding said work supporting means and thereby the work, and means for starting and stopping the feeding means at predetermined points.

16. In a sewing machine having a trunk and an overhanging arm carried thereby for the needle of the stitching mechanism, the combination of a bracket pivotally supported by the trunk at the rear end of said arm for shiftable movement toward and from the stitching mechanism, rotatable work supporting means carried by said bracket, means for intermittently feeding said work supporting means and thereby the work, and means for starting and stopping the feeding means at predetermined points thereby to leave a part of the work unstitched to permit the same to be turned inside out.

17. In a sewing machine having a trunk and an overhanging arm carried thereby for the needle of the stitching mechanism, the combination of a bracket pivotally supported at the rear end of the arm for shiftable movement toward and from the stitching

mechanism, rotatable work supporting means carried by said bracket, means for intermittently feeding said work supporting means and thereby the work, means for starting and stopping the feeding means at predetermined points, and means connected with said feeding means for severing the thread of a completed article.

18. In a sewing machine having a trunk and an overhanging arm carried thereby for the needle of the stitching mechanism, the combination of a bracket pivotally supported at the rear end of the arm for shiftable movement toward and from the stitching mechanism, rotatable work supporting means carried by said bracket, means for intermittently feeding said work supporting means and thereby the work, means for starting and stopping the feeding means at predetermined points, and means for automatically clamping and releasing the work.

19. In a sewing machine having a trunk and an overhanging arm carried thereby for the needle of the stitching mechanism, the combination of a bracket pivotally supported at the rear end of the arm for shiftable movement toward and from the stitching mechanism, rotatable work supporting means carried by said bracket, means for intermittently feeding said work supporting means and thereby the work, means for starting and stopping the feeding means at predetermined points, means for automatically clamping and releasing the work, and means connected with said feeding means for severing the thread of a completed article.

20. In a sewing machine having a trunk, a cylinder carried by the trunk, and stitching mechanism, a part thereof carried by the cylinder, the combination of a swinging bracket carried by the trunk and shiftable toward and from the cylinder, rotatable work supporting means carried by said bracket, and means carried by the cylinder for intermittently feeding said work supporting means and thereby the work.

21. In a sewing machine having a trunk, a cylinder carried by the trunk, and stitching mechanism, a part thereof carried by the cylinder, the combination of a swinging bracket carried by the trunk and shiftable toward and from the cylinder, rotatable work supporting means carried by said bracket, means carried within the cylinder and trunk for intermittently feeding said work supporting means and thereby the work, and means for starting and stopping the feeding means at predetermined points thereby to leave a part of the work unstitched to permit the same to be turned inside out.

22. In a sewing machine having a trunk, a cylinder carried by the trunk, and stitching mechanism, a part thereof carried by the cylinder, the combination of a swinging bracket carried by the trunk and shiftable

5 toward and from the cylinder, rotatable work supporting means carried by said bracket comprising a pair of clamp plates one shiftable toward and from the other, means for automatically releasing said plates, and means carried by the cylinder for intermittently feeding said work supporting means and thereby the work.

10 23. In a sewing machine having a trunk, a cylinder carried by the trunk, and stitching mechanism, a part thereof carried by the cylinder, the combination of a swinging bracket carried by the trunk and shiftable toward and from the cylinder, rotatable work supporting means carried by said bracket comprising a pair of clamp plates one shiftable toward and from the other, means for automatically releasing said plates, means carried within the cylinder and trunk for intermittently feeding said work supporting means and thereby the work, and means automatically operative for severing the thread of a previously completed article.

15 24. In a sewing machine having a trunk, a cylinder carried by the trunk, feed operating means carried by the cylinder, and stitching mechanism, a part thereof carried by the cylinder, the combination of a swinging bracket carried by the trunk and shiftable toward and from the cylinder, rotatable work supporting means carried by the bracket, and means connected with the feed operating means in the cylinder for intermittently feeding said supporting means and thereby the work.

20 25. In a sewing machine having a trunk, a cylinder carried by the trunk, feed operating means carried by the cylinder, and stitching mechanism, a part thereof carried by the cylinder, the combination of a swinging bracket carried by the trunk and shiftable toward and from the cylinder, rotatable work supporting means carried by the bracket, means connected with the feed operating means in the cylinder for intermittently feeding said supporting means and thereby the work, and means for automatically clamping and releasing the work carried by the work supporting means.

25 26. In a sewing machine having a trunk, a cylinder carried by the trunk, feed operating means carried by the cylinder, and stitching mechanism, a part thereof carried by the cylinder, the combination of a swinging bracket carried by the trunk and shiftable toward and from the cylinder, rotatable work supporting means carried by the bracket, means connected with the feed operating means in the cylinder for intermittently feeding said supporting means and thereby the work, means for automatically clamping and releasing the work carried by the work supporting means, and means operated by said feeding means for automatically severing the thread of a previously completed article.

27. In a sewing machine having stitching mechanism, the combination of a bracket supported for shiftable movement toward and from the stitching mechanism, a rotatable work support carried thereby and comprising a pair of changeable automatically releasable clamp plates, means for intermittently feeding said work support at a uniform speed whereby articles of various kinds may be stitched without varying the number of stitches.

30 28. In a sewing machine having stitching mechanism, the combination of a bracket supported for shiftable movement toward and from the stitching mechanism, a rotatable work support carried thereby and comprising a pair of changeable clamp plates, means for intermittently feeding said work support at a uniform speed whereby articles of various kinds may be stitched without varying the number of stitches, and means for automatically clamping and releasing the work.

35 29. In a sewing machine having stitching mechanism, the combination of a bracket supported for shiftable movement toward and from the stitching mechanism, a rotatable work support carried thereby and comprising a pair of changeable clamp plates, means for intermittently feeding said work support at a uniform speed whereby articles of various kinds may be stitched without varying the number of stitches, means for automatically clamping and releasing the work, and means connected with said feeding means for automatically severing the thread of a previously completed article.

40 30. In a sewing machine having stitch mechanism, the combination of a bracket shiftably supported for movement toward and from the stitch mechanism, work supporting means carried by said bracket and including a form or pattern, a cam roller co-operating with said pattern, means for holding the bracket and thereby the pattern in engagement with said cam roller, means for intermittently feeding said work supporting means, and means for starting and stopping the feeding means at predetermined points.

45 31. In a sewing machine having stitch mechanism, the combination of a bracket shiftably supported for movement toward and from the stitch mechanism, work supporting means carried by said bracket and including a form or pattern, a cam roller co-operating with said pattern, a spring for holding the bracket and thereby the pattern in engagement with said cam roller, means for intermittently feeding said work supporting means, means for starting and stopping the feeding means at predetermined points, and means for automatically clamping and releasing the work carried by the work supporting means.

50 32. In a sewing machine having stitch mechanism, the combination of a bracket

shiftably supported for movement toward and from the stitch mechanism, work supporting means carried by said bracket and including a form or pattern, a cam roller co-operating with said pattern, means for holding the bracket and thereby the pattern in engagement with said cam roller, means for intermittently feeding said work supporting means, means for starting and stopping the feeding means at predetermined points, means for automatically clamping and releasing the work carried by the work supporting means, and automatically operative cutting means.

33. In a sewing machine having stitch mechanism, the combination of a bracket, a work turn-table carried by the bracket and comprising a pair of clamping plates, feed operating means carried by the machine, means connected thereto for intermittently feeding said clamping plates and thereby the work, and trip mechanism for automatically stopping the stitch mechanism and the rotation of the clamping plates.

34. In a sewing machine having a forwardly extending cylinder, needle mechanism and looper mechanism, the latter carried by the cylinder, the combination of a bracket, a work turn-table carried by the bracket at one side of said cylinder and comprising a pair of clamping plates, feed operating means carried by the cylinder, means connected thereto for intermittently feeding said clamping plates and thereby the work, and trip mechanism for automatically stopping the stitch mechanism and the rotation of the clamping plates.

35. In a sewing machine having a forwardly extending cylinder, needle mechanism and looper mechanism, the latter carried by the cylinder, the combination of a bracket, a work turn-table carried by the bracket at one side of said cylinder and comprising a pair of clamping plates, feed operating means carried by the cylinder, means connected thereto for intermittently feeding said clamping plates and thereby the work, and trip mechanism for automatically stopping the stitch mechanism and the rotation of the clamping plates, said trip mechanism being also operative to maintain the stitching mechanism in operative position.

36. In a sewing machine having a trunk and a forwardly extending cylinder, needle mechanism and looper mechanism, the latter carried by the cylinder, the combination of a swinging bracket shiftably secured to the trunk, a rotary work turn-table carried by the bracket at one side of said cylinder and comprising a pair of clamping plates, feed operating means carried by the cylinder, means connected thereto for intermittently feeding said clamping plates, and trip mechanism for automatically stopping the stitch mechanism and the rotation of the clamping plates.

37. In a sewing machine having a trunk and a forwardly extending cylinder, needle mechanism and looper mechanism, the latter carried by the cylinder, the combination of a swinging bracket shiftably secured to the trunk, a rotary work turn-table carried by the bracket at one side of said cylinder and comprising a pair of clamping plates, means for automatically operating the clamping plates to clamp and release the work, feed operating means carried by the cylinder, means connected thereto for intermittently feeding said clamping plates, and trip mechanism for automatically stopping the stitch mechanism and the rotation of the clamping plates.

38. In a sewing machine having a trunk and a forwardly extending cylinder, needle mechanism and looper mechanism, the latter carried by the cylinder, the combination of a swinging bracket shiftably secured to the trunk, a rotary work turn-table carried by the bracket at one side of said cylinder and comprising a pair of clamping plates, means for automatically operating the clamping plates to clamp and release the work, feed operating means carried by the cylinder, means connected thereto for intermittently feeding said clamping plates, trip mechanism for automatically stopping the stitch mechanism and unclamping the work, and means for automatically severing the thread of a stitched article.

39. In a sewing machine having stitch mechanism and means for operating said stitch mechanism, the combination of a shiftable bracket, a work turn-table carried thereby and comprising a pair of rotatable clamp plates, means for intermittently rotating said plates, and trip mechanism operated from said turn-table and effective to stop the stitch mechanism and release the stitched work.

40. In a sewing machine having stitch mechanism and means for operating said stitch mechanism, the combination of a shiftable bracket, a work turn-table carried thereby and comprising a pair of rotatable clamp plates, means for intermittently rotating said plates, and trip mechanism operated from said turn-table and effective to stop the stitch mechanism and the rotation of said clamping plates and also effective to maintain the stitch mechanism and clamp plates in operative position at a predetermined time.

41. In a sewing machine having stitch mechanism and means for starting and stopping said stitch mechanism, the combination of a bracket shiftably supported for movement toward and from the stitch mechanism, a work turn-table carried by said bracket and comprising a pair of clamp plates, means for intermittently rotating said clamp plates and thereby the work, and trip mechanism for stopping the stitch mechanism and the rotation of said clamp plates and including a

pair of gears, one thereof having a pin, and means engaged by said pin during each rotation of the gears for operating the trip of said tripping mechanism.

5 42. In a sewing machine having stitch mechanism, the combination of a work support comprising a pair of clamp plates, means for automatically clamping and unclamping said plates, means for intermittently feeding the plates and thereby the work, and means for stopping the feeding of the plates at a predetermined time.

10 43. In a sewing machine having stitch mechanism, the combination of a work support comprising a pair of clamp plates, means for automatically clamping and unclamping said plates, means for intermittently feeding the plates and thereby the work, and means for stopping the feeding of the plates at a predetermined time, and comprising a pair of gears, one thereof having a pin, and trip means operated by said pin at predetermined times.

15 44. In a sewing machine having stitch mechanism, the combination of a work support comprising a pair of clamp plates, means for automatically clamping and unclamping said plates, means for intermittently feeding the plates, means for stopping the feeding of the plates at a predetermined time, and comprising a pair of gears, one thereof having a pin and trip means operated by said pin at predetermined times, and automatically operative cutting means located at the side 20 of said plates and operated by said feeding means.

25 45. In a sewing machine having a cylinder, stitch mechanism, a part thereof carried by the cylinder, and means for starting and stopping the stitch mechanism, the combination of a shiftably supported bracket, a work turn-table carried by the bracket and comprising a pair of rotary clamping plates, means for automatically clamping and unclamping said plates, a feed bar carried by the cylinder, means connected therewith for intermittently feeding the plates and thereby the work, trip mechanism operatively connected with the starting and stopping mechanism for holding the same in its operative position and for releasing the same at a predetermined time and including gearing having a projecting pin cooperating with a part of said trip mechanism at a predetermined time, and automatically operative cutting means carried by the cylinder.

30 46. In a sewing machine having stitch mechanism, treadle controlled transmitter mechanism, and an operating rod controlled by the transmitter mechanism, the combination of a rotatable work support having a central pivotal axis upon which it rotates, means for rotating it, and tripping means cooperating with said rod thereby to stop the rotation of said work support.

47. In a sewing machine having stitch mechanism, treadle controlled transmitter mechanism, and an operating rod controlled by the transmitter mechanism, the combination of a rotatable work support having a central pivotal axis whereby it rotates on a central pivot, means for rotating it, and tripping means operated from said rotatable work support and cooperating with said rod thereby to stop the rotation of said work support. 70 75

48. In a sewing machine having stitch mechanism, treadle controlled transmitter mechanism, and an operating rod controlled by the transmitter mechanism, the combination of a rotatable work support, means for rotating it, and tripping means operated from said rotatable work support and cooperating with said rod thereby to stop the rotation of said work support and comprising a spring controlled trip bar, a pair of meshing gears, a stud carried by one of said gears, a pivotally supported lever connected with said trip bar and having means cooperating with said stud. 80 85

49. In a sewing machine having stitch mechanism, treadle controlled transmitter mechanism, and an operating rod controlled by the transmitter mechanism, the combination of a rotatable work support comprising a pair of clamp plates one shiftable toward and from the other, pressure means for pressing said shiftable plate toward its companion plate, means operated by said rod for raising said clamping plate, means for rotating said plates, and tripping means cooperating with said rod thereby to stop the rotation of said work support. 90 95

50. In a sewing machine having stitch mechanism, treadle controlled transmitter mechanism, and an operating rod controlled by the transmitter mechanism, the combination of a rotatable work support comprising a pair of clamp plates one shiftable toward and from the other, pressure means for pressing said shiftable plate toward its companion plate, means operated by said rod for raising said clamping plate, means for rotating said plates, and tripping means cooperating with said rod thereby to stop the rotation of said work support and comprising a spring controlled trip bar, gearing rotated from said clamp plates, and means between said gearing and trip bar for shifting the bar. 100 105 110 115

51. In a sewing machine having a cylinder, stitch mechanism, a part thereof carried by the cylinder, a feed bar carried by the cylinder, treadle controlled transmitter mechanism, and an operating rod controlled by the transmitter mechanism, the combination of a shiftable bracket, a rotatable work support carried thereby and comprising a pair of clamp plates one shiftable toward and from the other, pressure means for pressing said shiftable plate toward its companion 120 125 130

- plate, means operated by said rod for raising said clamping plate, means connected with the feed bar for rotating said clamping plates, a spring controlled trip member cooperating with said rod thereby to stop the rotation of said work support at a predetermined time, gearing operated by said work support, and means controlled by said gearing for automatically shifting said trip member.
54. In a sewing machine having a cylinder, stitch mechanism, a part thereof carried by the cylinder, a feed bar carried by the cylinder, treadle controlled transmitter mechanism, and an operating rod controlled by the transmitter mechanism, the combination of a shiftable bracket, a rotatable work support carried thereby and comprising a pair of clamp plates one shiftable toward and from the other, pressure means for pressing said shiftable plate toward its companion plate, means operated by said rod for raising said clamping plate, means connected with the feed bar for rotating said clamping plates, a spring controlled trip member cooperating with said rod thereby to stop the rotation of said work support at a predetermined time, gearing operated by said work support, means controlled by said gearing for automatically shifting said trip member, and automatically operative cutting means carried by the cylinder at one side of said clamping plates and connected with the feed bar.
55. In a sewing machine having a cylinder, stitch mechanism, a part thereof carried by the cylinder, a feed bar carried by the cylinder, treadle controlled transmitter mechanism, and an operating rod controlled by the transmitter mechanism and having a notch, the combination of a swinging bracket shiftable toward and from the cylinder, means for holding said bracket in position adjacent to the cylinder, a rotatable work support carried by said bracket and comprising a pair of changeable clamp plates, one shiftable toward and from the other, pressure means for pressing said shiftable plate toward its companion plate, lever mechanism operated by said rod for raising said clamping plate against the action of said pressure means, ratchet mechanism connected with the feed bar for rotating said clamping plates intermittently, a spring controlled trip bar cooperating with the notch of said rod thereby to stop the rotation of the work support at a predetermined time, a pair of gears rotated from the work support one thereof having a pin, a pivotally supported lever connected with the trip member and having means cooperating with the gear pin for automatically shifting said trip bar, automatically operative cutting means carried by the cylinder at one side of said clamping plates and connected with the feed bar for operation thereby, an adjustable guide cooperating with the clamping plates for positioning the work, and a detachable work supporting table also cooperating with the clamping plates.
56. In a sewing machine having a trunk provided with a pair of forwardly projecting arms, stitch mechanism and means for operating it carried by said arms and trunk, the combination of an operating rod for controlling the stitch mechanism, a rotatable work support carried by said trunk, means for rotating it and thereby the work, means for automatically clamping and unclamping the work, automatically operative tripping means cooperating with said rod thereby to stop the rotation of said work support and the stitch mechanism and a single means co-

54. In a sewing machine having a cylinder, stitch mechanism, a part thereof carried by the cylinder, a feed bar carried by the cylinder, treadle controlled transmitter mechanism, and an operating rod controlled by the transmitter mechanism and having a notch, the combination of a swinging bracket shiftable toward and from the cylinder, means for holding said bracket in position adjacent to the cylinder, a rotatable work support carried by said bracket and comprising a pair of changeable clamp plates, one shiftable toward and from the other, pressure means for pressing said shiftable plate toward its companion plate, lever mechanism operated by said rod for raising said clamping plate against the action of said pressure means, ratchet mechanism connected with the feed bar for rotating said clamping plates intermittently, a spring controlled trip bar cooperating with the notch of said rod thereby to stop the rotation of the work support at a predetermined time, a pair of gears rotated from the work support one thereof having a pin, a pivotally supported lever connected with the trip member and having means cooperating with the gear pin for automatically shifting said trip bar, automatically operative cutting means carried by the cylinder at one side of said clamping plates and connected with the feed bar for operation thereby, an adjustable guide cooperating with the clamping plates for positioning the work, and a detachable work supporting table also cooperating with the clamping plates.

55. In a sewing machine having a trunk provided with a pair of forwardly projecting arms, stitch mechanism and means for operating it carried by said arms and trunk, the combination of an operating rod for controlling the stitch mechanism, a rotatable work support carried by said trunk, means for rotating it and thereby the work, means for automatically clamping and unclamping the work, automatically operative tripping means cooperating with said rod thereby to stop the rotation of said work support and the stitching mechanism, the operation of the treadle first clamping the work and starting the machine whereupon at a predetermined time the operation of the tripping means automatically stops the machine and simultaneously unclamps the work.

56. In a sewing machine having a trunk provided with a pair of forwardly projecting arms, stitch mechanism and means for operating it carried by said arms and trunk, the combination of an operating rod for controlling the stitch mechanism, a rotatable work support carried by said trunk, means for rotating it and thereby the work, means for automatically clamping and unclamping the work, automatically operative tripping means cooperating with said rod thereby to stop the rotation of said work support and the stitch mechanism and a single means co-

90

130

operating with said rod for controlling all of said mechanisms and the entire operation of the machine.

57. In a sewing machine having a trunk provided with a pair of forwardly projecting arms, stitch mechanism and means for operating it carried by said arms and trunk, the combination of an operating rod for controlling the stitch mechanism, a rotatable work support carried by said trunk, means for rotating it and thereby the work, means for automatically clamping and unclamping the work, automatically operative tripping means cooperating with said rod thereby to stop the rotation of said work support and the stitch mechanism and a single treadle cooperating with said rod for controlling all of said mechanisms and the entire operation of the machine.

58. In a sewing machine having a trunk provided with a pair of forwardly projecting arms, stitching mechanism carried by said arms, feed operating means carried by one of said arms, a bracket supported for shiftable movement toward and from said arms, a rotatable work support carried thereby, and means connected with the sewing machine feed operating means for directly and positively rotating said work support.

59. In a machine for sewing circular multi-ply articles, a rotatable work-feeding work table for receiving assembled plies of material and for stitch feeding the same to the machine needle, the said work table being adjustable relatively to the needle to adapt the same to articles of different diameters, a pressure plate movable into and out of engagement with the multi-ply assembly for holding the plies of material together and in engagement with the work table to be rotated thereby, and means for intermittently operating the work table in unison with the stitching operations of the needle.

60. In a machine for sewing circular multi-ply articles, a rotatable work-feeding work table for receiving assembled plies of material adapted to be stitched together at their rims and for stitch-feeding the same to the machine needle, the said work table being adjustable relatively to the needle to adapt the same to articles of different diameters, a pressure plate movable into and out of engagement with the multi-ply assembly for holding the plies of material together and in engagement with the work table to be rotated thereby, the work table and pressure plate having diameters less than that of the multi-ply assembly so that the circumferential edges of the assembly are exposed to be stitched together, and means for intermittently operating the work table in unison with the stitching operations of the needle.

61. In a machine for sewing circular multi-ply articles, a machine head, a rotatable work-feeding work table for receiving assembled

plies of material and for stitch-feeding the same to the machine needle, the said work table being adjustable relatively to the needle to adapt the same to articles of different diameters, a pressure plate movable into and out of engagement with the multi-ply assembly for holding the plies of material together and in engagement with the work table to be rotated thereby, the said pressure plate being adjustable to correspond to work table adjustments, and means for intermittently operating the work table in unison with the stitching operations of the needle.

62. In a machine for sewing circular multi-ply articles, a rotatable work-feeding work table for receiving assembled plies of material and for rotatably feeding the same to the machine needle, a pressure plate movable into and out of engagement with the multi-ply assembly for holding the plies of material together and in engagement with the work table to be rotated thereby, said pressure plate being mounted for free rotation so as to be rotated by operation of the work table, means for adjusting the pressure effective on said pressure plate, and means for intermittently operating the work table in unison with the stitching operations of the needle.

63. In a machine for sewing circular multi-ply articles, a rotatable work-feeding work table for receiving assembled plies of material and for stitch-feeding the same to the machine needle, a pressure plate movable into and out of engagement with the multi-ply assembly for holding the plies of material together and in engagement with the work table to be rotated thereby, said pressure plate being mounted for free rotation so as to be rotated by operation of the work table, means for adjusting both work table and pressure plate relatively to the needle to accommodate articles of different diameters, means for adjusting the pressure on the pressure plate, and means for intermittently operating the work table in unison with the stitching operations of the needle.

64. In a machine for sewing multi-ply articles, a work feeding mechanism including a rotatable table and a rotatable pressure plate between which the plies of the work assembly are held, means for intermittently operating said mechanism in relation to the sewing needle for stitching together the rims of the multi-ply assembly, and means for automatically releasing the pressure on the pressure plate and thereby releasing the work when a predetermined part of the rim of the work assembly has been stitched.

65. In a machine for sewing multi-ply articles, a work feeding mechanism including a rotatable table and a rotatable pressure plate between which the plies of the work assembly are held, operating means for intermittently actuating said mechanism in relation to the sewing needle for stitching together the

5 rims of the multi-ply assembly, and means for automatically stopping the operation of said operating means and for automatically releasing the pressure on the pressure plate and thereby releasing the work when a predetermined part of the rim of the work assembly has been stitched.

10 66. In a machine for sewing multi-ply articles, a work feeding mechanism including a pressure element for engaging the multi-ply work assembly, operating means for intermittently actuating said mechanism in relation to the sewing needle for stitching together the rims of the multi-ply assembly, and means automatically stopping the operation of said operating means and for automatically releasing the pressure on the pressure element and thereby releasing the work when a predetermined part of the rim of the work assembly has been stitched.

15 67. In a machine for sewing multi-ply articles, a sewing machine head, a work feeding mechanism including a rotatable table and a rotatable pressure plate between which the plies of the work assembly are held, means for intermittently operating said mechanism in relation to the sewing needle for stitching together the rims of the multi-ply assembly, and means for automatically elevating the pressure plate and thereby releasing the work when a predetermined part of the rim of the work assembly has been stitched.

20 68. In a machine for sewing circular multi-ply articles, a machine head, a rotatable work feeding work table for receiving assembled plies of material and for stitch feeding the same to the machine needle, a supporting plate for said work table adjustably mounted in said machine head, a pressure plate movable into and out of engagement with the multi-ply assembly for holding the plies of material together and in engagement with the work table to be rotated thereby, means for adjustably supporting said pressure plate on said machine head, and means for intermittently operating the work table in unison with the stitching operations of the needle.

Signed at Nyack, New York, this 25th day
50 of October, 1926.

JOHN P. WEIS.
